UNITED STATES PATENT OFFICE.

LEON E. LA BOMBARD, OF CHELSEA, AND MELVIN H. SIDEBOOTHAM, OF CLIFTONDALE,
MASSACHUSETTS, ASSIGNORS TO SPECIALTY AUTOMATIC MACHINE COMPANY, OF
CHELSEA, MASSACHUSETTS, A CORPORATION OF MASSACHUSETTS.

GLUER FOR BLANKS.

1,412,471.

Specification of Letters Patent. Patented Apr. 11, 1922.

Application filed February 6, 1920. Serial No. 356,704.

To all whom it may concern:

Be it known that we, LEON E. LA BOMBARD, a citizen of the United States, and resident of Chelsea, in the county of Suffolk, State of Massachusetts, and MELVIN H. SIDEBOOTHAM, a citizen of the United States, and resident of Cliftondale, in the county of Essex and State of Massachusetts, have invented certain new and Useful Improvements in Gluers for Blanks, of which the following is a specification.

This invention relates to devices for applying an adhesive substance, hereinafter referred to generically as glue, to articles such as foldable paper or pasteboard blanks, and the invention has particular reference to devices of this character which are mounted as attachments to box folding machines to supply stripes or bands of glue to surface portions of blanks while the latter are passing from a feeding mechanism to folding mechanism. Such devices usually employ a thin wheel or disk to apply the glue to the passing blanks, and the nature of the glue is such that if it gets anywhere other than onto the desired portions of the blanks, trouble is caused.

Some of the difficulties heretofore encountered are caused by leakage of glue around the wheel shaft which usually extends through both walls of the glue box. Others result from the escape of glue to a location above the usual clearer or "doctor" employed, from which location it gets smeared onto the blanks in excessive quantities. To overcome these objections are important objects of the present invention.

Other objects of the invention are to provide a gluer of the general type mentioned which can be properly lubricated without liability of the lubricant getting into the glue; to provide a gluer which will contain glue to a level any where above the shaft of the disk wheel without leakage, thereby reducing the size of the receptacle required for holding a given quantity of glue; to provide a structure which enables the disk to be located so close to one wall of the box that carrying belts for the blanks can run so close alongside the disk as to accommodate the smallest sizes of blanks; to provide a structure which will enable the level of the water used for transmitting heat to the glue to

be readily seen, thereby reducing the liability of burning out the heating unit usually employed for heating the water; and to provide other improvements which will be explained hereinafter.

To these ends the invention consists in the gluing device constructed, and having novel combinations, substantially as hereinafter described and claimed.

Of the accompanying drawings—

Figure 1 is a perspective view of the gluer, with a portion of its separable wall broken away, and omitting the removable cover which may be employed for the portion of the top which is shown as open.

Figure 2 represents a transverse vertical section.

Figure 3 represents a detail section on line 3—3 of Figure 2.

Figure 4 represents a detail section of the combined scraper or "doctor" and pocket, and a side elevation of a portion of the glue disk or wheel.

The main portion 12 of the box preferably comprises a casting so as to consist of one piece a side of which is open, when formed or being cleaned, said open side being closed water and glue tight by a plate 13 the upper edge of which is substantially flush with the top of the box (Fig. 2). Said box has apertured lugs 14 to be mounted on rods of the machine in which the gluer is to be used. Above the bottom of the box is a partition 15, preferably slightly inclined as shown in Figure 1, one end of the partition terminating in an upright wall 16. The partition 15 and wall 16 are parts of the casting.

A threaded hole 17 is for the connection of a heater, such as an electrical heating unit, which heater in practice extends under the partition 15. In practice water occupies the chamber below said partition and also a portion of the chamber between the wall 16 and the end of the box. Vapor or steam readily finds its way along the inclined bottom surface of the partition 15. If a cover is employed for the open portion of the top of the box, it will be one which is readily removable. Then the level of the water can be easily seen so that more water can be added if the level is getting so low that there is liability of the heating unit burning out, or so low that heat will not be properly

transmitted from the unit, by means of the water, to the glue above partition 15.

Also as an integral portion of the casting is a vertical web 18 (Figs. 2 and 3) having an enlargement at its lower edge to provide a bearing 19 in which is fitted a bushing 20. Mounted in the bushing 20 is the shaft 21 of the glue wheel 22 one face of which is recessed as at 23, the structure of the wheel being such that its glue-applying rim is offset laterally from the body of the wheel as best shown in Figure 2. The offset rim of the wheel extends above the plane of the top of the box, the edge of said top being recessed for this purpose (Fig. 1). Said recess, coacting with the inner face of the removable side plate 13, forms the necessary slot for the passage of the wheel rim. When the plate 13 is removed the recess can be easily cleaned if glue has accumulated therein. However the chief reason for this structure is that since the plate 13 is not relied upon for strength it can be quite thin as indicated in Figure 2 and since the wheel rim is close to the inner face of said thin plate it will also be at the minimum distance from the usual blank carrier travelling close to the outer face of plate 13 when the gluer and such carrier are relatively adjusted for 25 operation on very small blanks.

The inner ends of the bushing 20 is enlarged as shown in Figure 2 and serves as a packing to prevent escape of glue into and through the bearing. Therefore glue can occupy the pot to a level above the wheel shaft, or close to the top of the pot, without being liable to escape. To hold the shaft close to the enlarged inner end of the bushing, a nut 24 is fitted to the threaded outer 40 end of the shaft and secured in holding position by a screw 25.

Keyed to the shaft is a sprocket wheel 26 (Fig. 2) which is driven by a sprocket chain (not shown) which leads through apertures 45 in a protecting casing 27 for said wheel 26.

The shaft 21 is formed with a spiral groove 28 and the casting web 18 has a duct 29 leading in to a hole in the bushing. Lubricating oil from an oil cup 30 passes 50 through the duct 29 and the hole in the bushing from which it works into the spiral groove 28 to lubricate the shaft.

Rising from the top of the box casting is a post 31 in which is mounted a pin shaft 32 having an arm 33 the end of which has a threaded aperture for a screw 34 the lower end of which normally bears on the top of the box. Projecting laterally from the arm 33 and secured thereto by a screw 46 is a pin 55 35 to which is fixed a thin shoe 36 having a bevelled lower edge under which blanks to be glued are carried by any usual blank carrier. A collar 37 is secured to the pin shaft 32 by a set screw 38, and a spring 39 60 connecting said collar and the post 31 acts

to hold the arm 33 with its screw 34 normally bearing on the top of the box. Said screw, in practice, is usually set so as to prevent contact of the shoe 36 with the wheel 22, but close enough to it to ensure yielding pressure 70 on a passing blank to cause the under surface of said blank to take a stripe or band of glue from the wheel. The amount of pressure is varied by rotatively adjusting the collar 37 on the pin shaft 32.

The structure just described enables the shoe to yield without affecting its normal adjustment, if two or more superposed blanks should accidentally be fed between it and the glue wheel.

Mounted in a bearing in the upper corner of the box is a shaft 40 to which is secured the clearer or "doctor" 41 formed with a substantially vertical wall, two side walls, and a substantially horizontal wall which latter is slotted or recessed to provide an edge 42 which determines the thickness of the film of glue to be carried up by the wheel the rim of which travels through the slot. The space between the four described walls of the clearer and the periphery of the wheel forms a substantially triangular pocket the purpose of which will be presently described.

Secured to the end of the shaft 40 outside the rear wall of the box is an arm 43 the lower end of which carries a stud 44 in which is mounted a screw 45 in position for its inner end to bear against the end wall of the box. By adjusting the screw 45 the shaft 40 is rocked more or less so that the 100 edge 42 of the clearer may be varied in distance from the periphery of the wheel 22.

Some box folding machines for which the present gluer is designed as an attachment operate at a very high speed. Sometimes more than 60,000 blanks pass the wheel 22 in an hour. Of course the wheel is rotated at a peripheral speed approximately the same as the speed of travel of the blanks. At such a speed the wheel acts to "churn" the 110 glue in the box especially that glue which is adjacent the rising portion of the wheel. The clearer 41 is formed as hereinbefore described so as to act as a barrier to prevent the glue from acquiring such a condition due to churning as would result in its being forced out around the wheel above the "doctor" edge 42. The churned glue is mainly confined in the pocket within the four walls of the clearer and can only get out of that pocket past the edge 42, with the result that no glue can reach the top of the box. All of the glue carried up by the wheel and which is not transferred to passing blanks is carried back into the box by the wheel.

Having now described our invention, we claim:

1. In mechanism of the character described, a glue receptacle comprising a continuous bottom, two end walls and one side 130

- wall and a shaft bearing formed integrally, a removable plate forming the other side wall, a shaft mounted in said bearing, and a glue wheel carried by said shaft close to said removable plate.
2. In mechanism of the character described, a glue receptacle comprising a continuous bottom, two end walls and one side wall and a shaft bearing formed integrally, 10 a removable plate forming the other side wall, a shaft mounted in said bearing, a glue wheel carried by said shaft close to said removable plate, and means for conducting oil to said shaft bearing through an integral portion of the receptacle.
3. In mechanism of the character described, a receptacle comprising a casting presenting a bottom, two end walls, one side wall and an angular partition, a removable 20 side wall secured to the edges of the bottom and end wall of the casting, the angular partition being of a width to enable a tight joint to be formed between its edge and the removable side wall, and a glue wheel 25 in the compartment of the receptacle above said partition.
4. In mechanism of the character described a glue receptacle having an integral web depending from its top and formed with a shaft bearing, and a glue wheel having its shaft in said bearing, said web having a port for conducting oil to the shaft.
5. In mechanism of the character described, a glue receptacle having an integral 35 web depending from its top and formed with a shaft bearing, a glue wheel having its shaft extending through said bearing, and means for drawing the shaft outward through the bearing to prevent escape of glue past the wheel into said bearing.
6. In mechanism of the character described, a glue receptacle having a thin removable side wall, and a glue wheel projecting above the top of said wall and close 45 to it, said receptacle having an integral top portion one edge of which coacts with the top of the side wall to present a slot for the upper portion of the glue wheel.
7. In mechanism of the character described, a glue receptacle having a thin side wall, and a glue wheel projecting above the top of said wall and having a recessed outer face, the rim of the wheel being offset to present its outer face close to said side wall.
- 55 8. In mechanism of the character described, a glue receptacle having an integral top portion provided with a recess in its edge, a glue wheel mounted in the receptacle and presenting a portion of its periphery in and above said recess, and a removable side 60 plate close to the outer face of the wheel.
9. In mechanism of the character described, a glue receptacle having a top, a glue wheel projecting above said top, a thin edged blade yieldingly mounted above the 65 wheel, and means for adjustably limiting the normal distance between the blade and wheel.
10. In mechanism of the character described, a glue receptacle having a top, a glue wheel projecting above said top, a rock shaft having an arm provided with a screw, a spring normally holding the arm with its screw bearing on the top of the receptacle, and a shoe carried by said arm in position 70 to ensure contact of passing blanks with the glue wheel.
11. In mechanism of the character described, a glue receptacle, a rotary disk for transferring glue from the receptacle to 80 passing blanks, and a barrier device located within the receptacle at a point below the normal level of glue in the receptacle to prevent excessive churning of the glue by the rotary disk.
12. In mechanism of the character described, a glue receptacle, a rotary disk for transferring glue from the receptacle to 85 passing blanks, and a clearer having side portions extending past the sides of the disk, said clearer being recessed opposite the periphery of the disk.
13. In mechanism of the character described, a glue receptacle, a rotary disk for transferring glue from the receptacle to 90 passing blanks, and a pivotally mounted and adjustable clearer having a recessed portion through which the marginal portion of the disk passes.
14. In mechanism of the character described, a glue receptacle, a rotary disk for transferring glue from the receptacle to 95 passing blanks, a shaft having secured to it a clearer comprising two side walls, a substantially vertical wall and a substantially horizontal recessed wall whereby a pocket is formed inside said walls, and means for adjusting said shaft with its clearer.

In testimony whereof we have affixed our signatures.

LEON E. LA BOMBARD.
MELVIN H. SIDEBOTHAM.
